UNITED STATES PATENT OFFICE.

MAX LINDEMANN, OF EAST ST. LOUIS, ILLINOIS, ASSIGNOR OF ONE-HALF TO
EUGENE J. FEINER, OF ST. LOUIS, MISSOURI.

DEGERMINATOR AND HULLER.

1,364,288.

Specification of Letters Patent. Patented Jan. 4, 1921.

Application filed July 10, 1918. Serial No. 244,189.

To all whom it may concern:

Be it known that I, MAX LINDEMANN, a citizen of the United States, and resident of East St. Louis, in the county of St. Clair 5 and State of Illinois, have invented certain new and useful Improvements in Degermi- 60 nators and Hullers, of which the following is a specification, containing a full, clear, and exact description, reference being had to

10 the accompanying drawings, forming a part thereof.

My invention relates to degermi- 15 nators and hullers, and has for its object, the provision of a pimple plate, which is attached at the discharge end of the ordinary degermi- 20 nating and hulling roller. A further object is to increase the output of a degermi- 25 nator and huller, and at the same time reduce the amount of power consumed.

20 In the drawings,

Figure 1 is a top view of my device with the cover thrown back.

Fig. 2 is a longitudinal vertical view with parts in section.

25 Fig. 3 is a plan view of the pimple plate.

Fig. 4 is a side view of the same.

Fig. 5 is a face view of the discharge end of the housing.

30 In the construction of my device I employ an ordinary degermi- 35 nator 10 having a housing hinged in halves, as indicated by 11 and 12. In the portion 11 of the housing, I form an opening 13 through which the grain is fed to the interior of the housing. 40 Within the housing is located a shaft 14 upon which is securely attached a degermi- 45 nating roller 15; this roller being in the shape of a truncated cone.

This degermi- 50 nating roller is provided with feed veins 16, and back of the feed veins, pimpls or projections 17 are located; these pimpls or projections being arranged in spiral form so as to feed the grain toward the discharge end and extend approxi- 55 mately to the center of the longitudinal axis of the degermi- 60 nating roller. The rear portion of the degermi- 65 nating roller is provided with pimpls or projections 18, which are arranged at right angles to the horizon- 70 tal axis of the degermi- 75 nating roller. At the rear end of the roller I form a number of spiral grooves 19, the object of which is to feed the grain from the roller.

On the shaft 14 and abutting at the rear 80 85 90 95 100 105 110 end of the roller 15 I secure my improved

device, which consists of a pimple plate 20, having a hub 21 by which it is secured to the shaft. The vertical surface of this plate 20 is provided with a series of pimpls or pro- 60 jections 22, which act as additional degermi- 65 nators and hull removers, and the periphery of the plate is provided with spiral feeding grooves 23, which feed the grain over the edge of the plate.

The rear end of the housing 26^a is pro- 70 vided with a number of perforations 24, the object of which is to allow dust to escape from the device, and also act as an abrasive surface, and in the lower portion of this housing is hingedly attached a door 25, 75 which is held in closed position by means of the lever 26, and the weight 27. The ob- 80 ject of having this lever and weight is so that the pressure exerted on the inside of the machine, or in other words, the dis- 85 charge of the grain may be regulated.

The operation of my device is as fol- 90 lows: The grain having been fed into the housing through the opening 13, is fed to- 95 ward the spirally placed pimpls 17 by means of the feeding wings or veins 16. The grain is then carried forward by the pimpls 17, and comes in contact with the pimpls 18. The constant supply of grain being fed forward forces the grain past the pimpls 18 into the spiral grooves 19 on the roller and 23 on the pimple plate. The grain will then lodge between the pimpls 22 and the rear perforated end 26^a of the housing, and when a sufficient amount of grain has lodged in this space, the door 25 will open and allow the degermi- 100 nated and hulled grain to pass from the housing into a suitable receptacle.

By the use of my device, I have found that it is possible to speed the machine up to a much higher rate, accomplish more work, and with less power, than in the devices at present used, for the reason that in the devices of the present time, all of the degermi- 105 nating and hull removing is done by the surface of the roller only; the rear end of the roller merely serving as a pocket, and performing no function whatever.

Having fully described my invention, what I claim is:

1. A degermi- 110 nator and huller comprising a housing, a shaft extending centrally there- through, a tapered degermi- 115 nating roller located within the housing and mounted on

said shaft, a removable pimple plate mounted against the larger end of the degenerating roller and secured to said shaft, said pimple plate being provided on its face with 5 a series of projecting pimples and on its periphery with feeding grooves, a perforated closure for the housing adjacent the pimple plate, a discharge opening formed in said perforated closure and a weight controlled door for closing said discharge opening.

2. A degenerator and huller comprising a housing with a perforated discharge end, a shaft extending centrally through 15 said housing, a tapered degenerating roller mounted within the housing and secured to said shaft, said tapered roller being provided on its ends with feed grooves, pimples formed on the roller intermediate the feed

grooves, a removable pimple plate secured 20 against the larger end of the degenerating roller and on said shaft, said removable pimple plate being provided on its face adjacent the perforated end with pimples and coating with the edges of the perforations 25 for facilitating the degenerating and hulling of the grain, and provided on its periphery with feed grooves coinciding with the feed grooves formed on the large end of the degenerating roller.

In testimony whereof I have signed my name to this specification in the presence of two subscribing witnesses.

MAX LINDEMANN.
